STITCHING AND TRIMMING MACHINE

John D. Karle, Roselle Park, N. J., assignor to
The Singer Manufacturing Company, Elizabeth, N. J., a corporation of New Jersey

Application May 26, 1934, Serial No. 727,645

16 Claims. (Cl. 112—124)

This invention relates to sewing machines and more particularly to a sewing machine for simultaneously stitching and trimming material.

The several features of the present invention will be clearly understood from the following description and accompanying drawings in which:

Figure 1 is a front elevation, partly in section, of a sewing machine having my improved trimming mechanism embodied therein.

Figure 2 is a side elevation of the sewing machine head and trimming mechanism as viewed from the left in Figure 1.

Figure 3 is a plan sectional view on the line 3—3 of Figure 1.

Figure 4 is a sectional view taken along the line 4—4 of Figure 3.

Figure 5 is a sectional view taken substantially along the line 5—5 of Figure 2.

Figure 6 is a disassembled perspective view of the cutting wheel and the parts used to secure it to its actuating means.

Figures 7, 8 and 9 are sectional views taken along the lines 7—7, 8—8 and 9—9, respectively, of Figure 3.

Figure 10 is a vertical sectional view of a modification of the anvil roller and Figure 11 is a side elevation as viewed from the left of Figure 10.

As shown, my improved trimming or pinking mechanism is incorporated in the well known "Singer" 95 Class machine. This machine comprises a bed 10, a standard 11 rising therefrom, and an overhanging bracket-arm 12 terminating in a hollow head 13. Journaled in suitable bearings in the bracket-arm 12 is a main shaft 14 which carries at its forward end the needle-bar and take-up operating cranks 15, 16, respectively. The needle-bar crank is connected by means of the usual link 17 to the needle-bar 18 which carries the eye-pointed needle 18'.

The main-shaft 14 carries the usual balance-wheel 20 and secured to the shaft 14 is a bevel-gear 21 which meshes with a gear 22 on the upper end of the vertical shaft 23 carrying at its lower end the bevel-gear 24 which meshes with the gear 25 on the loop-taker actuating shaft 26 which carries the loop-taker 27 and is journaled in bearing lugs 19 and 19' below the bed 10.

The feeding mechanism is of the usual construction and comprises the feed-lift eccentric 28 and feed-advancing eccentric 28' which, through the pitmans 30, 30, operate the feed-lift rock-shaft 32 and feed-advancing rock-shaft 32'.

The elements comprising the feeding adjusting mechanism for varying the throw of the feed-dog are of ordinary construction and, as herein

illustrated, comprise a bell-crank lever 29 pivotally secured to a boss on the standard of the machine by a pivot-pin 29'. One leg of the bell-crank lever 29 is provided with a hand-piece 29^a and the other leg 29^b is pivotally secured to a link 31 which is secured to pitman 30 by the pivot-screw 33. This construction is old and well known and is shown in the patent to Cox, 1,062,696, dated May 27, 1913.

The feed-lift rock-shaft 32 has fixed thereto 10 an arm 34 carrying a pin 35 which enters a U-shaped slot in one end of the feed-bar 36 which carries the feed-dog 36'. The other end of the feed-bar is connected by means of a pivot-screw 37 to an arm 38 carried by the feed-advancing 15 rock-shaft 32'.

Fixed to the main-shaft 14 is an eccentric 39 encircles by a block 39' which is embraced by the bifurcated end 40 of a bell-crank lever 41. The lever 41 is pivoted for rocking movement on a pivot-pin 42 carried by the lug 43 fixed to the head 13 of the machine. The end 44 of the lever 41 is bifurcated to receive the square block 45 which is carried by a pivot-screw 46 fixed to an arm 47 which is secured to a short shaft 48 journaled in the rearwardly extending arms 49 of a frame 50.

The frame 50 is adjustably secured to the bed of the machine by the downwardly extending projections 53 and 53' which dovetail with the ears 52' of the block 52 secured to the bed of the machine by the screws 51 (Figs. 2 and 9). It will be obvious from the foregoing that the frame 50 may be shifted longitudinally of the block 52 in order to move the frame 50 closer or nearer the 30 stitch-forming mechanism. To hold the frame 50 in its adjusted longitudinal position on the slide-block 52, I have provided a shouldered screw 55 which extends through a suitable aperture in the projection 53' of the frame 50 and is threaded 35 into a locking block 56 (Fig. 9). When the screw 55 is tightened the inclined side 57 of the block 56 is clamped against the ear 52' of the supporting slide-block 52, thereby frictionally clamping the frame 50 in its desired position.

Fixed to the shaft 48 is an arm 59 formed with a projection 61 and a T-shaped slide-way in which is fitted a slide-block 60 formed with a pivot-stud 62. The block 60 is apertured and tapped to receive the threaded end of the adjustment 50 screw 63 which is formed with shoulders 64 and 65 located on opposite sides of the projection 61 on the arm 59.

Carried by the stud 62 and slidably therewith is an indicator element 66 and a flanged bushing 55

67 which extends through a slot 68 in the arm 69 and is held on the stud 62 by the knurled headed nut 70.

The arm 69 is fixed by the screws 71 to a driving clutch member 72 which is freely rotatable on the shaft 73 and supported thereby. The clutch-member 72 is formed with three spaced projections 74 the outer faces of which are curved so as to fit freely within the driven cylindrical clutch member 75 which is fixed to the shaft 73 by the screws 75'. Between the projections 74 are cut-away parts forming pockets for the gripping rollers 76. One face of each of the projections 74 is formed with a pocket in which a spring 77 is located having one of its ends re-acting against the bottom of the pocket and its other end re-acting against a plunger 78 which contacts one of the rollers 76 and forces it outwardly.

To prevent retrograde or backward movement 20 of the clutch-member 75 and shaft 73 when the clutch-member 72 is moved in a direction opposite to the arrow shown in Fig. 4, I have provided a clutch-holding member 79 similar in construction to the driven clutch-member 72. To secure the clutch-holding member 79 against rotation there is secured to the member 79 by the screws 80 a bracket 81 having laterally extending feet 82 which are adjustably fixed to the bed 10 of the machine by the means of the screws 84 entering 30 the slots 83. The shaft 73 is freely rotatable in the clutch-member 79 which is formed with chambers in which the rollers 85 are located and spring-pressed plungers 86 are provided for forcing the rollers outwardly. The driving clutch and holding clutch are similarly disposed relative to the shaft 73 and, therefore, when the driving clutch is moved in the direction of the arrow in Fig. 4, the rollers 76 move outwardly and grip the driven element 75 causing it to move with the 40 driving member, when the driven element 75 is thus turned the rollers 85 of the locking clutch move inwardly towards the holding member 79 to permit the element 75 to turn freely. When the driving clutch member is moved in a direction opposite to the arrow in Fig. 4 the rollers 76 will be moved inwardly out of driving contact with the element 75 and any tendency to turn the element 75 in this direction will be prevented by the rollers 85 of the holding clutch.

50 The driven element 75 is fixed to the shaft 73 by the screws 75' and this shaft is journaled in an adjustable eccentric bushing 88 carried by the frame 50. The bushing 88 is formed with a flange portion 89 provided with suitable openings 89' for the purpose of turning the bushing relative to the frame. To hold the bushing 88 in its adjusted position a portion of the frame 50 is split and a clamping screw 90 draws the split portion tightly about the bushing.

60 The shaft 73 is provided with a centrally located aperture 91 which extends longitudinally of the shaft and the end of the shaft is formed with a cylindrical projection 95 and a rib 92. The cylindrical projection 95 extends through the aperture 96 in a locking disc 94 and the rib 92 is received by the diametrical recess 93. A cutting or pinking wheel 97 having a centrally located aperture 98 which receives the cylindrical projection 95 is held on the end of the shaft 73 by the headed bolt 99 which extends through the longitudinal aperture 91 in the shaft 73 and is held therein by a nut 100. The bolt 99, cutting wheel and disk 94 are all locked in driving relation with the shaft 73 by means of a pin 101

which extends through suitable apertures 102 and 102' in the cutting wheel and locking disk.

The cutting wheel 97 cooperates with a platen or anvil roller located below the bed of the machine and having its outer periphery extending through a suitable opening in the throat-plate 103 to a position in which the outer periphery of the roller is in substantially the same horizontal plane as the upper-face of the throat-plate. The anvil roller comprises an outer race-member 104 and an inner race-member 105 with a series of anti-frictional elements 106 therebetween. Disks 107 are provided for retaining grease in and to prevent foreign materials from entering the raceway. The inner race-member 105 is carried by the headed bushing 108 in which the loop-taker actuating shaft 26 is journaled.

In order to bring the trimming mechanism close to the stitch-forming mechanism, the outer race-member 104 is formed with an extension 20 104' which overhangs and partially surrounds the loop-taker 27. To support the overhang of the ring 104, I have provided two standard ball-bearings 109 which are secured by the screws 110 to the reduced and offset ends 111 of the studs 112 25 rotatably carried by the bearing lug 19 and secured thereto by nuts 113. It will be obvious from the foregoing that the nuts 113 may be loosened and the studs 112 turned in order to adjust the ball-bearing 109 relative to the outer 30 surface of the race-member 104'.

In Figures 10 and 11, I have shown a modification of the platen roller. As shown, the cutting element which cooperates with the cutting wheel comprises a ring 115 which encircles the 35 loop-taker 27. The inner face of the ring 115 is formed with a strengthened shoulder 116 to prevent undue distortion. The ring is supported on anti-frictional bearings 117 each of which comprises two standard ball-bearings 119 held 40 between two washers 120 on the reduced and offset end 123 of the stud 122 by the screws 121. The studs 122 are supported by the bearing lug 19 and are held therein by the nuts 124. It will be obvious that the nuts 124 may be loosened 45 and the studs turned to adjust the anti-frictional bearing 117 relative to the cutting wheel 97 in order to adjust the ring 115 relative to the cutting wheel. The washers 120 have a larger diameter than the roller-bearings 119 and therefore extend beyond the outer periphery of the ball-bearing to prevent lateral movement of the ring 115.

Operation

When the machine is operated, the cam 39 oscillates the bell-crank lever 41 about its pivot 42, and the lever 41, through the arm 47, oscillates the shaft 48 in its bearing. The oscillatory movement of the shaft 48 imparts an up and down vibratory motion to the lever 69 by means of the 60 arm 59 and pivot-stud 62. The vibratory motion of the lever 69 through the "one-way" clutch imparts an intermittent rotary movement to the driven clutch-member 75 and shaft 73 which carries the cutting wheel 97. The cutting wheel 65 is intermittently rotated in a clockwise direction as viewed in Figure 2 and it will be understood that the cam 39 and the actuating mechanism are so arranged as to synchronize the movement of the cutting wheel with the feed-dog.

The amount of rotary movement given the cutting wheel 97 may be varied by loosening the nut 78 and then rotating the shouldered adjusting screw 63 which moves the sliding block 60 and stud 62 longitudinally of the arm 59 to vary 70

the vibratory movement of the lever 69. When the feeding mechanism is adjusted to vary the throw of the feed-dog it is also necessary to adjust the vibratory movement of the lever 69 to vary the rotary movement of the cutting wheel. To facilitate the making of these adjustments so that the feed-dog and cutting wheel will feed the material the same amount between successive needle reciprocations I have provided the feed-adjusting hand-piece 29^a with an indicator 125 and the standard of the machine with a plate 126 having graduations thereon which correspond to the graduations 66' on the arm 59. By simply placing the indicators 66' and 125 at corresponding points on the graduated plates the feed-dog and cutting wheel feed the material the same distance simultaneously.

If it is desired to move the cutting wheel towards or away from the needle the thumb-screw 20 55 and the screws 84 are loosened and the entire assembly shifted longitudinally of the bracket 52, the block 45 and pivot-pin 46 being of sufficient length to permit this adjustment.

It will be obvious that by loosening the screw 25 90 the eccentric bushing 88 may be turned in the frame 50 to adjust the cutting wheel relative to the platen roller or ring.

While I have shown and described my invention applied to a lock-stitch machine of the rotary hook type, it may readily be applied to other types of machines.

From the foregoing description considered in connection with the accompanying drawings, the construction, manner of operation and several 35 advantages of my improved stitching and pinking machine will be clearly and fully understood. It is apparent that such a machine has a wide variety of uses, and it will be understood that the form, construction and arrangement of the 40 elements employed may be varied. Therefore, the privilege is reserved of resorting to all such legitimate changes therein as may be fairly embodied within the spirit and scope of the appended claims.

Having thus set forth the nature of the invention, what I claim herein is:—

1. The combination with a sewing machine having a work-support, a reciprocatory needle located above the work-support and a loop-taker located below the work-support and cooperating with said needle to form stitches, of a cutting wheel rotatably supported above said work-support, means for actuating said cutting wheel, a ring having a substantially uniform size of opening and its outer periphery extending through an opening in said work-support and cooperating with said cutting wheel to sever material, and supporting means for said ring, said supporting means being located below and engaging the outer periphery of the ring which extends through the opening.

2. The combination with a sewing machine having a work-support, a reciprocatory needle located above the work-support and a rotary hook located below the work-support and cooperating with said needle to form stitches, of a cutting wheel rotatably supported above said work-support, means for actuating said cutting wheel, a ring encircling said rotary hook and having its outer periphery extending through an opening in said work-support and cooperating with said cutting wheel to sever material and a plurality of antifrictional elements for rotatably supporting said ring, said cutting wheel,

ring and anti-frictional elements being disposed in substantially the same vertical planes.

3. In combination with a sewing machine having a reciprocatory needle-bar, a rotatably supported cutting wheel, means for actuating said wheel, a ring having its outer periphery cooperating with said cutting wheel to sever material, and means for rotatably supporting said ring at spaced points on its outer periphery and substantially in the vertical plane of the cutting wheel.

4. In combination with a sewing machine having a reciprocatory needle-bar, a rotatably supported cutting wheel, means for actuating said wheel, a ring having its outer periphery cooperating with said cutting wheel to sever material, means for rotatably supporting said ring at spaced points on its outer periphery, and means for adjusting said ring relative to said cutting wheel.

5. In combination with a sewing machine having a reciprocatory needle-bar, a rotatably supported cutting wheel, means for actuating said wheel, a ring having its outer periphery cooperating with said cutting wheel to sever material, means for rotatably supporting said ring at spaced points on its largest diametrical peripheral portion, and means for adjusting said cutting wheel relative to said ring.

6. In combination with a sewing machine having a reciprocatory needle-bar, a cutting wheel, means for actuating said cutting wheel, a circular member cooperating with said cutting wheel to sever material and means for supporting said member at spaced points on its outer periphery, said cutting wheel, circular member and supporting means being disposed in substantially the same vertical plane.

7. In combination with a sewing machine having a reciprocatory needle-bar, a cutting wheel, means for actuating said cutting wheel, a circular member cooperating with said cutting wheel to sever material and anti-frictional elements engaging the outer periphery of the member at its largest diametrical peripheral portion for rotatably supporting said member.

8. In combination with a sewing machine having a work-support, a reciprocatory needle located above said work-support, a loop-taker cooperating with said needle to form stitches and located below said work-support, a cutting wheel rotatably supported above said work-support, means for actuating said cutting wheel, a member encircling said loop-taker and having its outer periphery cooperating with said cutting wheel to sever material, and means engaging the outer periphery of the member at its largest peripheral portion for rotatably supporting said member.

9. In combination with a sewing machine having stitch-forming and feeding mechanism including a four motion feed-dog, a cutting wheel, means for imparting intermittent motion to said cutting wheel, means for synchronizing the movement of said cutting wheel with the movement of said feed-dog, a circular member cooperating with said cutting wheel to sever material and means for rotatably supporting said member at spaced points on its outer periphery and at its largest peripheral portion.

10. In combination with a sewing machine having a reciprocatory needle-bar, a cutting wheel, means for actuating said cutting wheel, a ring cooperating with said cutting wheel to sever material, and antifrictional means below the

- diametrical center line of the ring for rotatably supporting said ring, said cutting wheel, ring and anti-frictional means being disposed in substantially the same vertical plane.
- 5 11. In combination with a sewing machine having a work-support, a reciprocatory needle located above said work-support, a loop-taker cooperating with said needle to form stitches and located below said work-support, a cutting wheel 10 rotatably supported above said work-support, means for imparting a step-by-step movement to said cutting wheel, a ring encircling said loop-taker and cooperating with said cutting wheel to sever material and antifrictional elements located substantially in a vertical plane containing the cutting wheel below the diametrical center line of the ring for rotatably supporting said ring.
- 15 12. In combination with a sewing machine having a work-support, a reciprocatory needle located above said work-support, a loop-taker cooperating with said needle to form stitches and located below said work-support, a cutting wheel rotatably supported above said work-support, means for imparting a one-way intermittent motion to said cutting wheel, a ring having its outer periphery cooperating with said wheel to sever material, means below the diametrical center line of the ring and in substantially the same vertical plane as the cutting wheel for rotatably supporting said ring, and means for holding said ring against lateral movement.
- 20 13. A sewing machine having in combination a work-support, an overhanging bracket-arm rising from said work-support, a needle-bar actuating shaft journaled in said overhanging arm, a needle-carrying bar actuated thereby, a loop-taker located below the work-support, a frame fixed to said work-support, a shaft journaled in 25 said frame, a rotary cutting wheel carried by said shaft, a one-way clutch carried by said shaft, a cam carried by the needle-bar actuating shaft, a bell-crank lever actuated by said cam and means connecting said bell-crank lever with said 30 one-way clutch, said bell-crank lever and said last-named means being disposed in rear of the overhanging bracket-arm.
- 35 14. A sewing machine having in combination
- a bed formed with a bearing lug, a bushing carried by said lug and having a portion extending therefrom, a shaft journaled in said bushing, a loop-taker secured to said shaft, a ball-bearing carried by the extending end of said bushing, 5 said ball-bearing comprising an inner race member, an outer race member formed with a portion which overhangs the loop-taker, and a series of balls interposed between said members, anti-frictional elements disposed beneath the outer 10 race member and engaging the outer periphery of the member directly below the overhanging portion, a cutting wheel cooperating with the periphery of the outer race member, and means for imparting a step-by-step movement to said 15 cutting wheel.
15. A sewing machine having in combination, sewing instrumentalities including a reciprocatory needle and a rotary hook cooperating therewith to form stitches, a cutting wheel, means for 20 actuating said wheel, a ring cooperating with said wheel to sever material and having a portion which encircles said rotary hook, and antifrictional means for rotatably supporting said ring, said supporting means including antifrictional 25 elements engaging the inner periphery of said ring and a plurality of antifrictional elements engaging the outer periphery of said ring and located beneath the portion of the ring which encircles said hook. 30
16. A sewing machine having in combination a work-support, sewing instrumentalities including a reciprocatory needle located above said work-support and a loop-taker located below said work-support and cooperating with said needle 35 to form stitches, a trimming mechanism comprising a rotary cutting member and a platen member cooperating therewith, one of said members being located above said work-support, the other of said members being located below said 40 work-support and encircling said loop-taker, means for supporting said last mentioned member including antifrictional elements located below said member and being disposed in substantially the same vertical plane as said members, 45 and means for actuating one of said members.

JOHN D. KARLE.
